UNITED STATES PATENT OFFICE.

JOHN ROY STARK, OF RACINE, WISCONSIN, ASSIGNOR TO WEBSTER ELECTRIC COMPANY, OF RACINE, WISCONSIN, A CORPORATION OF WISCONSIN.

MAGNETO.

Application filed November 19, 1921. Serial No. 516,270.

To all whom it may concern:

Be it known that I, JOHN ROY STARK, a citizen of the United States, and resident of Racine, in the county of Racine and State 5 of Wisconsin, have invented a certain new and useful Improvement in Magnétos, of which the following is a full, clear, concise, and exact description, reference being had to the accompanying drawings, forming a 10 part of this specification.

This invention relates to magneto generating devices, such as are commonly employed to ignite the charges in the cylinders of internal combustion engines, and is particularly concerned with an arrangement of this 15 character in which a device commonly called an impulse starter is employed.

In the drawings:

Figure 1 is a longitudinal vertical section 20 through the device;

Figure 2 is a view substantially on the line 3—3 of Figure 1, looking in the direction of the arrows;

Figure 3 is a view looking toward the 25 right end of the device, as seen in Figure 1, with the end member of the frame removed; and

Figure 4 is a vertical section substantially 30 on the line 5—5 of Figure 1, looking in the direction of the arrows.

The object of the present invention is to provide a device of the above character which shall be compact, shall consist of relatively few parts, and the assembly of the 35 parts shall be such as to reduce to the minimum the probability of their becoming displaced and rendered inoperative.

A feature of the invention is the provision of a device of the above character 40 which is self-contained and wherein the pinion or pulley for transmitting rotary motion to the rotor of the magneto may be mounted directly on the shaft projecting from the magneto housing.

45 A further feature of the invention and one contemplated by the feature above noted is the provision of a device of this character in which the number of fixed bearings is reduced to a single bearing at each end of the rotor shaft.

A still further feature of the invention is the provision of telescopically arranged shaft elements which will permit the rotary

movement of the rotor and its shaft in relation to the driving shaft without permitting 55 said shafts to get out of alignment.

Other features and advantages of the invention will appear as the description of the device progresses.

Referring now to the drawings, 1 indicates the usual permanent magnet, the free ends of which extend longitudinally and engage opposite sides of the base member 2 which may consist of any suitable non-magnetic material. In engagement with the inner surfaces of the legs of the magnet 1 are the pole pieces 3 and 4. These pole pieces may be cast within the base member 2, as disclosed in applicant's prior application, Serial No. 405,959, filed August 25, 70 1920. The base member 2 has laterally extending flanges 5 provided with perforations 6 by means of which the magneto may be secured in place.

Mounted within the cylindrical space 75 formed by the pole pieces 3 and 4 and the adjacent portions of the base member 2 is the rotary element of the magneto. This rotary element may be of any preferred construction, but, as shown in the present application, it consists of a plurality of substantially I-shaped strips or plates 7 of magnetizable material which are secured in fixed relation by means of the rivets or other securing devices 8. Mounted within the rectangular spaces within the sides of the strips 7 are a pair of insulating channels 9 and 10, of fibre or other material, about which the insulated wire forming the coils of the rotor 80 is wound. In order to prevent undue spreading of the coils beyond the laminae 7, the pins 11 are provided. Extending centrally through the laminae 7 is the rotor shaft 90 12.

Fixed to the shaft 12 in any desired manner, at one end of the windings or coils 13, 95 is a disc 14 of conducting material to which is secured one end of the wire forming the windings or coils 13. The shaft 12 at the left end thereof, as viewed in Figure 1, is centrally bored, as at 15, to receive the conducting pin 16, a sleeve 17 of insulating material being provided between the shaft and the pin 16. A conductor 18 passes through an opening in the shaft 12 and is electrically joined to the pin 16. This conductor 18 joins 100 the pin 16 to one end of the wire forming the

coils 13. Thus one end of the wire forming the coils 13 is joined to the plate 14 and the other end of the wire is joined to the pin 16, it being understood, of course, that the 5 conductor 18 is insulated from the shaft 12.

Arranged adjacent to one edge of the permanent magnet 1 is an end piece 19 provided with an outwardly curved flange 20. The flange 20 is provided with a channel 21, 10 within which may be positioned felt or similar material 22 for engaging with the edge of the magnet 1. The end member 19 is also provided with a shouldered depression 23 which receives a flange 24 projecting 15 from the base member 2. The end piece 19 is provided, opposite the base member, with the annular flange 25.

Centrally located within the annular flange 25 and connected thereto by the web 26 is a bearing seat 27. Within the bearing seat 27 is the bearing 28 of any desired material which receives one end of the rotor shaft 12.

Supported by this web member is a spring 25 pressed brush which bears against the disc 14 and thus forms the other outlet terminal for the rotor windings or coils 13. I have not shown this arrangement of brush, as it forms no important part of the present invention.

Non-rotatably secured to the reduced end of the shaft 12, as by the spline 33 and the nut 34, is the cam 35 which causes the operation of the interrupter contacts of the magneto. The interrupter mechanism is housed in the space enclosed by the flange 25 and a sheet metal cover 79, which cover fits over the flange 25. This interrupter mechanism forms no important part of the present invention and consequently I shall not describe the same.

The transformer coils and the condenser of the magneto are mounted in the space within the upper half of the magnet 1. The 45 primary winding, or windings, of this transformer are connected with the rotor windings and with the interrupter mechanism through conventional leads, the connections of which constitute no part of the present 50 invention.

The end member 19 is provided with the oil cup 95 which communicates through the downwardly extending opening 96 with a circular groove 97. Within the outer surface 55 of the bearing member 28 groove 97 communicates with the lubricating wick 98.

We will now describe the portion of the device which includes the impulse starter mechanism. The end of the rotor opposite 60 that already described is provided with the end piece or plate 99, which is provided with the outwardly and then inwardly extending flange 100. The flange 100 at its inner edge is provided with the bearing support 101, 65 within which is the bearing member 102, of

any suitable material. The right end of the shaft 12, as viewed in Fig. 1, has a reduced portion 103, to which, adjacent the rotor coils, is rigidly secured the collar 104. Rigidly secured to the collar 104 in any desired manner is the plate 105. The plate 105 is provided at diametrically opposite sides thereof with the laterally extending lugs 106 and 107 (see Fig. 3). Concentrically arranged about the reduced portion 103 of the 70 shaft 12, and within the bearing 102, is the drive shaft 108. Rigidly secured to the inwardly extending end of the shaft 108, in any desired manner, is the plate 109. The plate 109 is provided with four laterally extending flanges 110 (see Fig. 4) and a pair of radially extending arms 111. The four laterally extending flanges 110 combine to form a drum about which is arranged the 75 clock spring 112, one end of which is secured to one of the flanges 110, the other end being secured to the flange 106 which projects from the plate 105 secured to the rotor shaft.

Projecting from the plate 105 secured to the rotor is a bearing lug 113. Pivottally supported on the bearing lug 113 is a pawl or detent 114, having the weighted end 115. Extending outwardly from the plate 109, which is secured to the sleeve shaft 108, is a pair of lugs 116 and 117, the purpose for 80 which will presently appear. Secured to the end piece 99, as by the screws 118, is an abutment or stop plate 119 provided with a shoulder 120 arranged to be engaged by the detent 114. Non-rotatably fixed to the outwardly extending portion of the shaft 108, as by the spline 121 and nut 122, is the gear wheel 123, by means of which rotary movement is transmitted to the rotary element 85 of the magneto. An oil cup 124 is provided which communicates through the opening 125 and the arcuate grooves 126 with the lubricating wick 127. The right end of the fibre or paper lining 84 of the receptacle 68 is closed by means of a block 128 of fibre or 90 other material which is secured to the lining 84 by means of screws 129 which are received by the threaded lugs 130 secured to the lining 84. The end strip 99 is provided 95 opposite the plate 128 with the spring member 131, the inwardly extending ends of which are arranged to engage the plate 128 when the end member 99 is in position. The member 99 is secured in position on the base member by four screws 132, each of which 100 passes through an opening in the end plate and is received by a threaded opening in the base member 2.

When the device is in operation, power is transmitted from a rotary element of the engine, through any suitable medium, to the gear or pulley 123, thus causing the shaft 108 to be rotated. At all normal speeds of rotation, the rotor shaft 12 rotates with shaft 108, due to the tension of the spring 105 110 115 120 125 130

112, which tends to retain the lug 106 carried by the plate 105 fixed to the rotor in engagement with the arm 111 carried by the plate 109 fixed to the driving shaft 108.

5 When, however, the shaft 108 is rotated at a very slow speed, as when the engine is being started, the pawl 114, which is fixed to the rotor element through the medium of the lug 113 and plate 105, will engage the 10 abutment 120 and temporarily prevent rotation of the rotor. The continued rotation of the shaft 108 now acts to tension the spring 112. As the shaft 108 continues to rotate, the lug 117 carried by the plate 109 15 engages the weighted end 115 of the pawl and forces the detent portion 114 out of engagement with the abutment 120, and permits the rotor to be rapidly rotated, due to the energy which has been stored in the 20 spring 112. On release, the rotary movement of the rotor is terminated by the lugs 106 and 107, projecting from the edges of the plate 105, coming into engagement with the radially extending arms 111 carried by the 25 plate 109. This rapid rotation of the rotor through a portion of a revolution acts to create a high potential in the secondary and thus produces a spark of sufficient intensity to ignite the charge in the cylinder of the 30 engine. The engagement of the detent with the abutment 120 is brought about due to the action of gravity on the weighted end 115 of the detent. The detent 114 is so positioned in the magnetic field that the magnetic 35 attraction does not resist the outward movement of the detent 114, but on the contrary may be employed to slightly assist such movement. When operating at higher speeds, as when the engine is running, the 40 centrifugal force acting on the weighted end 115 of the detent forces the operative end of the detent inwardly out of the path of the abutment 120.

It will thus be seen that in the structure 45 above described, a magneto having an impulse starter has been provided which, from all external appearances, is similar to a magneto having no impulse starter. The bearings for the magneto shafts are 50 contained in the end plates, and the driving gear or pulley is mounted directly on the end of the shaft projecting through one of the end plates.

In the structure described, the telescoping 55 arrangement of the end of the driven shaft within that part of the driving shaft, which is received by the bearing, practically assures that the two shafts will be maintained in alignment, and by this structure 60 the possibility of the operative parts of the resilient coupling between the two shafts being displaced is reduced to the minimum.

Although but a single embodiment of the invention is disclosed in the drawings and 65 specification, it is to be understood that

modifications of the device are contemplated, and that the invention is to be limited merely by the scope of the appended claims.

What I claim is:

1. In a magneto, a driving shaft, a disc 70 fixed thereto, laterally extending flanges on said disc, a spring positioned about said flanges, a driven shaft, a plate fixed thereto adjacent and substantially parallel to said disc, and a laterally extending finger carried by said plate arranged to overlie said flanges, one end of said spring being attached to one of said flanges, and the other end to said finger. 75

2. In a magneto, a driving shaft, a disc 80 fixed thereto, laterally extending flanges on said disc, a spring wound about said flanges, a driven shaft, a plate fixed thereto adjacent and substantially parallel to said disc, a laterally extending finger carried by said 85 plate arranged to overlie said flanges, one end of said spring being attached to one of said flanges, and the other end to said finger, and a radial extension on said disc adapted to co-operate with said finger to maintain 90 said disc and plate in normal relative position.

3. In a magneto, a driving shaft, a disc 95 fixed thereto, laterally extending flanges on said disc, a spring wound about said flanges, a driven shaft, a plate fixed thereto adjacent and substantially parallel to said disc, a laterally extending finger carried by said 100 plate arranged to overlie said flanges, one end of said spring being attached to one of said flanges, and the other end to said finger, a pawl carried by said plate, a fixed stop arranged to be engaged thereby, and means on said disc for disengaging said pawl from 105 said stop.

4. In a magneto, a driving shaft, a disc 110 fixed thereto, laterally extending flanges on said disc, a spring wound about said flanges, a driven shaft, a plate fixed thereto adjacent and substantially parallel to said disc, a laterally extending finger carried by said 115 plate arranged to overlie said flanges, one end of said spring being attached to one of said flanges, and the other end to said finger, a radial extension on said disc adapted to co-operate with said finger to maintain said disc and plate in normal relative position, a pawl carried by said plate, a fixed stop arranged to be engaged thereby, and means on said disc for disengaging said pawl from 120 said stop.

5. In a magneto, a driven shaft, a driving shaft, cover or end plates, one for each end of said magneto, bearings, one in each of said plates, said driving shaft being arranged to project through one of said bearings, one end of said driven shaft being arranged to project into the other said bearing, the other end of said driven shaft being 125 telescopically arranged within a portion of 130

said driving shaft, a disc fixed to said driving shaft, a plate fixed to said driven shaft, and a spiral spring positioned about said shafts having one end secured to said disc 5 and the other end to said plate.

6. In a magneto, a driven shaft, a driving shaft, cover or end plates, one for each of said magneto, aligned bearings, one in each of said plates, one end of said driven shaft 10 being arranged to project through one of said bearings, said driving shaft being received by the other said bearing, the other end of said driven shaft being telescopically arranged within said driving shaft, a disc 15 fixed to said driving shaft, a plate fixed to said driven shaft, and a spring positioned about said shafts and having one end secured to said disc and the other end secured to said plate.
7. In a magneto, a driven shaft, a driving shaft, cover or end plates, one for each end 20

of said magneto, bearings, one in each of said plates, said driving shaft being arranged to project through one of said bearings, one end of said driven shaft being arranged to project into the other said bearing, the other end of said driven shaft being telescopically arranged within a portion of said driving shaft, a disc fixed to said driving shaft, laterally extending flanges on 25 said disc, a spring positioned about said flanges, a plate fixed to said driven shaft, and a laterally extending finger carried by said plate, one end of said spring being attached to said finger, the other end of said 30 spring being attached to one of said flanges.

In witness whereof, I hereunto subscribe my name this 10th day of November, 1921.

JOHN ROY STARK.
